UNITED STATES PATENT OFFICE.

HENRY HOWARD, OF BROOKLINE, MASSACHUSETTS.

BAUXITE-DIGESTER.

1,175,147.

Specification of Letters Patent. Patented Mar. 14, 1916.

Application filed June 24, 1914. Serial No. 847,163.

To all whom it may concern:

Be it known that I, HENRY HOWARD, a citizen of the United States, residing at Brookline, in the county of Norfolk and 5 State of Massachusetts, have invented certain new and useful Improvements in Bauxite-Digesters, of which the following is a specification.

This invention is an apparatus for digesting bauxite in strong solutions of caustic soda, for the preparation of aluminate solutions.

In the preparation of aluminate solutions, as in the well-known Bayer process, the 15 bauxite is digested in caustic soda solutions of 42° to 47° Baumé, under a pressure of 40 to 70 pounds per square inch. This necessitates the use of steam at comparatively high pressures, say 150 to 250 pounds per 20 square inch, rendering it difficult and dangerous, as well as uneconomical, to employ jacketed vessels, and making it impracticable to construct them in large units. Moreover, the character of the solvent and 25 of the solution is such that it is extremely difficult to maintain any joints below the liquid level.

The present invention provides a form of digester in which the requisite temperatures 30 and pressures may be maintained economically and without difficulty or danger, which is free from tendency to leakage, of which the contents may be freely circulated, and which may be easily and safely constructed 35 in very large units.

A preferred embodiment of the invention is illustrated in the accompanying drawing, wherein the figure is a central vertical section.

40 The apparatus illustrated comprises a strong steel shell 1, properly riveted and calked, and completely covered by a heat-insulating jacket 2. The steam coil 3 is located within the shell, concentric therewith, and spaced from the vertical walls to provide an upward path for the circulating liquor. This coil is constructed of seamless tubing, the lengths being welded together, and welded to the flanges 4, which are riveted to the shell. The turns of the coil are supported within the shell by standards 5 carried by the shell, in such manner that the coil is entirely free to expand and contract without communicating strains to the shell. 50

55 A valved inlet opening for the charge is provided at 6, and a manhole at 7, both in

the cover of the digester, above the liquid level. The valved outlet 8, in the bottom of the digester, is connected to a discharge pipe 9, which leads upwardly to a receiving tank 60 10, the arrangement being such that the pressure within the digester is utilized to elevate the solution to avoid pumping.

A vertical shaft 11 carrying propeller blades 12 enters the digester through a stuffing-box and bearing 13 in the center of the cover, and is hung in suitable external bearings not shown. The propeller 12 is a circulating device, in contradistinction to an agitator, and is preferably rotatable in such 70 direction as to circulate the charge downwardly in the central region of the digester and upwardly around its periphery and in contact with the steam coil 3. This circulation is preferably rendered more definite 75 by providing an open-ended cylindrical casing 14, suitably supported within the coil 3 and encircling the propeller 12.

This apparatus has successfully solved one 80 of the serious engineering difficulties which have been encountered for many years in the practice of the Bayer process.

I claim:

1. An apparatus for digesting bauxite with alkaline solutions, comprising a closed vessel adapted to withstand heavy internal pressures and provided with a heat-retaining covering, a steam coil mounted in proximity to the shell of the vessel, said coil supported from said shell but free to move relatively thereto, and an axial rotary circulating device constructed to maintain a definite circulation of the contents of the vessel. 85

2. An apparatus for digesting bauxite with alkaline solutions, comprising a closed vessel adapted to withstand heavy internal pressures and provided with a heat-retaining covering, a steam coil mounted in proximity to the shell of the vessel, said coil supported from said shell but free to move relatively thereto, and an axial rotary circulating device constructed to maintain a definite circulation of the contents of the vessel, said device comprising an open-ended casing 90 within the steam coil, and a rotary propeller arranged to circulate the contents of the vessel downwardly through said casing and upwardly over said coil. 100

3. An apparatus for digesting bauxite with alkaline solutions, comprising a closed vessel adapted to withstand heavy internal pressures and provided with a heat-retain- 110

ing covering, a steam coil mounted in proximity to the shell of the vessel and practically the entire height thereof, said coil supported from said shell but free to move relatively thereto, and an axial rotary circulating device constructed to maintain a definite circulation of the contents of the vessel.

4. An apparatus for digesting bauxite with alkaline solutions, comprising a closed vessel adapted to withstand heavy internal pressures and provided with a heat-retaining covering, a steam coil mounted in proximity to the shell of the vessel and practically the entire height thereof, said coil supported from said shell but free to move rela-

tively thereto, and an axial rotary circulating device constructed to maintain a definite circulation of the contents of the vessel, said device comprising an open-ended casing within the steam coil near the bottom thereof, and a rotary propeller arranged to circulate the contents of the vessel downwardly through said casing and upwardly over said coil.

In testimony whereof I affix my signature in presence of two witnesses.

HENRY HOWARD.
